(57) **CLAIM**

The ornamental design for a magnetic tip for a carpenter's measuring tape, as shown and described.

DESCRIPTION

FIG. 1 is a left side perspective view of the magnetic tip for a measuring tape embodying my new design;

FIG. 2 is a bottom view thereof;

FIG. 3 is a left side elevation view thereof (the right side elevation view being a mirror image);

FIG. 4 is a top view thereof;

FIG. 5 is a front view thereof; and,

FIG. 6 is a rear view thereof.

1 Claim, 1 Drawing Sheet
